UNITED STATES PATENT OFFICE.

RICHARD W. UHLIG, OF ARLINGTON, NEW JERSEY, ASSIGNOR TO ATLAS TYPEWRITER CO., INC., OF NEW YORK, N. Y., A CORPORATION OF NEW YORK.

TYPE-WRITER.

1,193,949.

Specification of Letters Patent.

Patented Aug. 8, 1916.

Application filed May 21, 1913. Serial No. 769,001.

To all whom it may concern:

Be it known that I, RICHARD W. UHLIG, a citizen of the United States, residing at Arlington, in the county of Hudson and State 5 of New Jersey, have invented certain new and useful Improvements in Type-Writers, of which the following is a specification.

This invention relates to typewriting machines of the down-strike type-bar class, its 10 object being to produce a machine of such simplicity and cheapness of construction that it can be put on the market at an exceptionally low price, and yet have as far as possible the capabilities of the high priced 15 standard machines. The new machine has or may have the same key board as the most commonly used high priced typewriters; it has a light and powerful action, there is the minimum liability of interference of the 20 type bars, and the types strike a sufficiently sharp blow for the production of several clear manifold copies.

In the accompanying drawings, Figure 1 is a plan of the machine, being partly broken 25 away in horizontal section; Fig. 2 is a vertical transverse section; Fig. 3 is a similar section showing one type bar in the act of striking; Fig. 4 is a sectional front view in planes to the rear of the keys, the key-levers 30 being omitted; Fig. 5 is a fragmentary end elevation showing the carriage and its appurtenances at the right hand end of the machine; Fig. 5^a is a fragmentary rear elevation showing the right hand end of the 35 platen and its adjacent parts; Fig. 6 is a fragmentary front elevation in a section just in front of the slides F showing two of these slides and their connected and adjacent parts; Fig. 7 is a perspective view showing 40 one of the slides and its connection with the key lever B; Fig. 8 is a fragmentary vertical mid-section through the slotted segment f showing the band g' detached; Fig. 8^a is a fragmentary front view of part of the 45 band g'; Fig. 9 is a fragmentary plan partly in horizontal section showing the escapement; Fig. 10 is a fragmentary end elevation of part of the carriage; Fig. 11 shows 50 part of Fig. 10 in a different position; Fig. 12 is a sectional side view showing a modification.

Referring to the drawings, A designates a frame, which may in general be of the customary design, so that it both supports and

largely incloses the working parts; B B are 55 the key levers carrying the usual keys B', C C are the type bars, D is the platen or impression roller, and E is as a whole the carriage.

Each of the key-levers B is pivoted on a 60 fulcrum a, and its rear arm engages an upright actuating part, best formed as a slide F so that as the key is depressed this slide is lifted. This engagement is best made by forming a lug on the piece F and turning it 65 laterally so that it stands transverse to the direction of the rear arm of the key lever, the end of the latter projecting through a slot cut in this lug b, as shown in Fig. 7, so as to engage between shoulders formed by 70 the ends of the slot. The slot confines the key-lever laterally and keeps it in correct engagement with the slide. The upper part of the slide F is formed with teeth constituting a rack c which engage with pinion 75 teeth c' on the type bar C. The type bar carries preferably three types, the middle one of which normally strikes the impression roller or platen D, the latter being shifted as will be described in case it is desired to 80 print either the outer or the inner type. The type bars are arranged in radial order, as shown in Fig. 1, their printing heads turned so that when thrown back to the printing point the type heads will each occupy the 85 same position transversely of the platen, as is understood.

The key levers have their pivots a at varying distances from the printing point, these 90 pivots being so disposed that each lever has the same ratio of front or key arm to rear arm, so that the keys have an equal dip. The pivots are formed by providing each lever with a transversely projecting pin, which pin enters into notches in a split pivot post 95 d projecting upwardly from a plate G which is fixed in place in the frame A; the key lever resting in the slit or kerf which is machined across the post. Each lever has its own individual spring e which may be variously constructed, being shown as a coiled spring guided on a rod, and reacting against a top plate e' which is arc shaped and fastened to the main frame.

The type bars C are pivoted in a slotted 105 segment f having an unslotted base fastened to the main frame. Its upper portion has radial slots in vertical planes, each slot re-

ceiving the rack portion c of the slide F and the pinion portion c' and adjacent part of the type bar, so that these are kept in mesh and guided laterally by the slot. In addition, the segment f is formed with a horizontal slot f' in its front side, which slot enters it deeply enough to form a seat for the pivotal wires g of the several type bars. To prevent the forward displacement of the parts and at the same time to conceal the slots as viewed from the front, a band g' of metal plate is carried around the curved front face of the segment, being fastened thereto at its ends by screws. This band g' thus guides the upper end of the slides F and keeps their teeth in mesh with the pinion teeth c' . The lower ends of the slides F are suitably guided, being shown as moving freely through slots in a plate h which is fastened to the plate G . To enable the engagement of the band g' with the slides c to be individually adjusted either in the original assembling or to take up wear, the band is formed with a series of individual tongues or fingers g'' , as shown in Figs. 8 and 8^a, which fingers can be bent more or less to engage their respective slides.

The letter-feed movement is in general of the ordinary kind, comprising a universal bar H overlying the rear arms of the key levers so as to be lifted upon the depression of any key, and connected at its ends to lever arms H' fixed on a rock shaft H^2 carrying a rear arm H^3 , which is connected by an adjustable link h to the escapement J . A spring h^2 , pulling upward on an arm h^3 , retracts the parts and keeps the universal bar pressed down upon the key levers. A special spacing lever I is provided, mounted like the other key levers and carrying a space bar I' , which is shown as extending in front of the keys.

The escapement J is shown in its two opposite positions in Figs. 2 and 3. It comprises a rack bar hung between pivots i at its opposite ends, which pivots are carried by a supporting piece i' . The rack bar carries a rack j fixedly attached to it, and a rack j' mounted to slide longitudinally moving as usual a distance of one tooth, and retracted by a light spring j^2 . These two escapement racks engage a carriage rack k which is fixedly attached to the carriage. When no key is depressed, as in Fig. 2, the carriage rack engages the movable escapement rack j' ; when any key is depressed the link h pulls down upon its connection with the escapement bar J , and tilts the latter to the position shown in Fig. 3, thereby first engaging the rack j with the carriage rack k , and then releasing the rack j' therefrom, whereupon this rack is retracted by its spring. Upon the release of the key the escapement tilts back to its first position, the rack j' engaging the carriage rack teeth just

before the rack j is released therefrom; thereupon the light spring j^2 yields and the carriage feeds forward one space.

For releasing the escapement to permit the carriage to be moved backward, a sliding release bar K is provided having one end upturned to form a handle K' , and mounted to slide obliquely by the engagement of its slots l with fastening studs l' , sliding thus against the tension of a spring l^2 . When retracted by this spring its rear edge is out of contact with the escapement, but when thrust to the right by the pressure against its handle K' , its oblique movement brings its rear edge into engagement with an upwardly projecting tooth m fixed to the movable rack j' , and it presses back this tooth and thereby thrusts back the rack j' to the position shown in Fig. 9, whereby its rack teeth are pressed back out of engagement with the teeth of the rack k , as shown in said figure. To permit this, the movable rack j' is constructed so as to have a double movement, being adapted to move rectilinearly in the ordinary letter-space feeds, and to turn around a pivot so as to swing backwardly in this release motion. A simple construction is that best shown in Fig. 9, where the rack j' has a slot n engaging a pin n' so that it may either move longitudinally upon the pin or may tilt around the pin. The spring j^2 is arranged to pull obliquely, so that it acts to restore the rack j' in either movement. To accomplish this the rack is formed with a rearward arm n^2 to which the spring is attached and which makes the rack essentially an elbow lever as to its tilting movement.

The carriage E comprises a base E' which slides between stationary bars p attached to the main frame, balls being interposed in grooves as usual to make the motion nearly frictionless. The rack k is attached to the rear bar of the base E' . The platen D is supported in bearings formed in a platen carrier comprising horizontal end pieces L which are connected by longitudinal rods L' forming a horizontally sliding frame, the bars L serving as slides moving in slide-ways formed on uprights E^2 which project upwardly from the ends of the base E' . The sliding frame L enables the platen to be moved either forward or back from its normal central position in order to receive the impression of either of the three types carried by the type bars.

With the preferred arrangement shown, the middle type on each bar prints a lower case letter, the inner type (nearest the pivot) prints a capital letter, and the outer type prints a figure or other character. The shift from lower case to capitals is accomplished by pressing down a capital shift key M' mounted on a lever M ; and the shift to print figures or other of the outer types is accom-

plished by pressing down a figure shift key N' mounted on a lever N . Pressing the former key moves the platen forward to bring the printing point under one of the inner types, this being the position shown in Fig. 3; pressing the latter key, moves the inner platen backward to bring the printing point under one of the outer types.

The shift mechanism will now be described. The shift levers M N are pivoted on a rod q and are prolonged rearwardly by arms M^2 N^2 respectively which as shown in Fig. 1 are curved toward the middle of the machine and terminate beneath the platen. On their rear ends these arms carry cam plates P and P' respectively. These cam plates have oblique cam slots either of which is adapted to engage a longitudinal bar Q which is hung beneath the carriage on levers Q' at opposite ends of the carriage, the upper arms of these levers being forked and engaging the platen spindle at the opposite ends of the platen. The levers Q' and bar Q constitute a rigid frame having parallel motion so that in whatever position the carriage may be the cam grooves of the plates P P' when they engage the bar Q will impart to it, and through the levers to the platen, an equal and parallel movement to front or rear. The shift movement is shown in Fig. 3, which shows only the capital shift key lever M and its connections, the figure shift lever being omitted. Each plate P P' has in addition to the oblique cam slot an upright face P^2 , the two faces P^2 when the parts are in normal position being approximately vertical, and guiding the bar Q between them, as shown in Fig. 2, so as to keep it in its central position and thereby hold the platen in its normal line of travel for printing lower case types. The shift levers M N are retracted by springs q' shown in Figs. 1 and 3, these springs being preferably helical compression springs held on rods passing through them, and reacting upwardly against the under side of the frame.

A shift key lock is provided shown best in Fig. 4; it consists of a lever R , its upper arm serving as a handle, and its lower arm having lock shoulders on opposite sides, so that when turned to one side it engages and locks the lever M when depressed, and when turned to the other side it engages and locks the lever N . To release either shift key the lever R may be pushed back toward its middle position; or by merely pressing down on the depressed key its engagement with the lock lever will be released and the lock lever will be restored to its central position by its spring r , which is a leaf spring tending to press it from either side toward the middle.

To render the writing visible, the ribbon which is advanced over the printing point before the impression of the type, is retract-

ed during the return swing of the type bar. The ribbon s is carried between spools S S' and through a ribbon guide S' having fingers forming slides through which the ribbon passes, as shown in Fig. 1. This guide S' lies nearly horizontally, being pivoted at its front part to an elbow-lever T having its short arm T' engaged by an arm T^2 attached to the universal bar H and projecting upwardly and rearwardly therefrom so as to overlie the arm T' . The upper arm of the lever T has a cross piece engaged by a spring s' . In the normal position of the parts the guide S' is held in its forward or retracted position by the arm T^2 , as shown in Fig. 2, thus exposing the printing point (shown at α in Fig. 1). When a key is struck, the rising of the universal bar releases the lever T' and the spring s' tilts the lever T and advances the guide S' to the position shown in Fig. 3.

Inasmuch as the actual location of the printing point is changed by the operation of the shift keys, it is necessary to effect an equal shift of the ribbon guide, in order that the ribbon may follow the printing point. This is accomplished by pivoting the lever T at t to a slide t' which moves in forward or backward direction in ways t^2 (Fig. 2), and is so connected to the platen carrier L L' as to participate in the shifting movements of the platen. This connection is made by fixing to the slide t' a projecting fork u which engages a rod u' , which rod forms part of the platen carrier L L' , being supported from the front rod L' by means of rigid connecting pieces at its opposite ends. Thus as the platen is shifted forwardly or backwardly of its normal mid position, it carries the slide t' with it, and consequently equally shifts the fulcrum t , and hence the lever T and ribbon guide S' , thus carrying the ribbon to the new location of the printing point.

The ribbon is advanced in a usual manner by its spools being geared to pinions on upright shafts v v' which at their lower ends carry bevel gears v' , one or other of which is driven by bevel pinions v^2 on a longitudinal shaft U having bearings in the main frame and projecting at its opposite ends, so that the operator may press upon the projecting end and thereby throw the shaft toward the opposite ends, thereby throwing one pinion out of gear and the other into gear, and reversing the ribbon. The shaft has grooves U' engaged by a spring U^2 . The shaft U carries a ratchet wheel w (Fig. 2) which is operated by a pawl w' hung on a lever w^2 having fork arms embracing between them the universal bar H .

The carriage has the usual paper holder V . The platen is turned to impart the line feed by means of the usual ratchet wheel D' engaged by a pawl y carried on a line

feed lever D². The feed pawl works between stops one of which is adjustable to vary the line spacing. The forward stop is y' (Fig. 5) and the rear stop is z, the latter being movable to vary the line spacing. The stop z is an arm turning on the platen shaft and having a slight movement toward or from a plate E² fixed to the platen carrier and having pins between which the stop z is held. To shift the stop, it is pressed to the right, this being resisted by a light spring z' (Fig. 1) whereby to withdraw a pin z² which it carries from one of two holes in the plate E², and upon being displaced 10 is dropped into the other hole. The plate E² and its holes is shown in Fig. 10, the stop z being shown in dotted lines. The ratchet clicks against a roller or pin carried by a lever arm W pressed toward the ratchet 15 by a spring to hold the platen after the line feed. When it is desired to turn the platen freely, this arm W is pushed away by moving a cam lever W' the lower arm of which has a cam face which engages the lever W and throws it away from the ratchet wheel, 20 so that this roller clears the ratchet teeth. 25

For causing the types to register accurately at the printing point, the usual gage 14 is provided, having as usual a tapered 30 notch into which the type bars enter. This gage is carried on a bridge piece 15 fastened by screws 16 to the opposite ends of the segment f, whereby it is easily removable by unscrewing these screws. The bridge piece 35 15 also serves to hold down the ribbon guide S, having for this purpose fingers 17 17', the latter being elongated at 18 to serve also for holding down the paper. The paper is held around the platen by a guide roller 19 and fingers 20 as usual.

The type bars fall back against an arc-shaped cushion 21, of felt or other noise-deadening material, which is held in a groove formed between flanges 22, 23 on the 40 main frame.

This invention admits of improvements in the proportioning of the type bars whereby superior results are attained. The type bars instead of being of a length approximating 5 inches, are reduced to approximately 3 inches in length or less. The head carrying the three types may be of the same size and weight as heretofore; but the type bar extending thence to the pivot is 50 not only shorter, but is made of lighter material than heretofore, this being made possible because of its diminished length, which permits of the same stiffness being gained by the use of a thinner and narrower bar, so that the weight of the type bars need not 55 exceed one-quarter of those heretofore used. Thus the inertia of the type bar is greatly diminished, particularly so as the weight of the type head is brought so much nearer the 60 pivot that its effective weight is correspond-

ingly reduced. Hence even if other proportions were unchanged, the type head will be set in motion with less resistance. Heretofore the type bars have ordinarily moved through an arc of about a quarter circle or 70 90 degrees; but in this new machine they are given a movement approximating 180 degrees. A three-inch bar moving 180 degrees travels approximately 9 inches, whereas as a five-inch bar moving 90 degrees travels 75 approximately 7½ inches, so that the shortened bars having the greater travel, strike the heavier blow without adding to the work imposed upon the keys. In fact the new machine has both greater manifolding 80 power and a lighter touch than any typewriting machine heretofore built. The advantage of the long travel for the type is apparent from the law of acceleration of falling bodies, which applies similarly to 85 any mass accelerated by the application of mechanical force.

In a down-strike machine, giving the bars a throw of 180 degrees, brings the types face up, where they lie normally against the 90 cushion 21, where they are readily accessible for inspection or cleaning.

The type bars lie normally in vertical planes radiating from a point forward of the printing point and nearly coinciding with the center of the gage 14. The type bars are thus most closely related at their pivotal ends, diverging thence to their heads. It results from this that there is such divergence of the type head paths that the types may clear each other when an approaching and receding type bar pass at less than 90 degrees from the striking point. The opportunity for high speed is thus afforded, since while one type bar is receding 100 its successor may be advancing to print. Thus for more than one half of the stroke of the type bars they are non-interfering.

The machine is rendered very compact by reason of the short type bars and their being so closely assembled. This is possible only through the construction of the slotted segment f, which enables the type bars to be brought very closely together.

The various features of improvement result in a typewriting machine of extremely simple, light, and compact construction, having all the essential capabilities of the standard high priced machines, and yet of such cheapened construction that it can be 115 produced at about one-quarter the cost. In lightness of touch, speed, and manifolding power, this machine excels the heretofore standard machines.

It is not strictly necessary to my invention 125 that the type bars have the full 180 degrees swing which is preferable. Fig. 12 shows diagrammatically an arrangement in which the cushion 21 is so elevated that the type bar moves through only about 120 130

degrees. This arrangement will somewhat increase the speed, but will slightly diminish the manifolding power. Otherwise it has the same advantages already explained.

- 5 The carriage is provided with a marginal space bar 25 pivoted to it at points 26 at opposite ends, its main portion being extended parallel with the platen and having a series of holes 27 into which may be inserted a pin 28 the end of which projects beneath the bar and serves to stop it against a fixed stop 29 attached to the main frame of the machine. The pin 28 is preferably screwthreaded and screws into the holes to hold it securely. The pin is set in one or other of the holes according to the width of margin desired. When it is desired to write a full line the frame 25 is lifted to carry the pin 28 over the stop 29. For so lifting 10 the frame a handle 30 is provided projecting upwardly from it and serving as a lifting lever. In printing such full line the pin 28 should clear the stop 29 without stopping the feed, and for this purpose the stop 29 is beveled so that it allows the pin to ride over it in moving in the active direction. The handle 30 projects up adjacent to the line space handle D² so that the operator may conveniently operate both simultaneously by pinching them between the thumb and finger of the right hand, whenever he desires in making the return line feed and return stroke of the carriage to carry the latter beyond the position for 15 which the margin stop is set.
- The invention may be modified in many respects as will be apparent. Its novel features are those set forth in the claims.
- Those features of the typewriting machine 20 herein set forth which relate to the case shift and the corresponding ribbon shift, are not herein claimed, being claimed in my divisional application No. 857,465 filed August 19, 1914.
- 25 That feature of the typewriting machine herein set forth which relates to the margin stop, is not claimed herein, being the subject matter of divisional application No. 858,013 filed August 22, 1914.
- 50 I claim as my invention:—
1. In a typewriter, a down-strike type-bar moving through approximately a half circle, having pinion teeth, an upright slide having rack-teeth at its upper end engaging said pinion teeth, and a key-lever connected to the lower part of said slide to lift it and impart the printing movement to the type-bar.
  2. In a typewriter, a platen, a series of 55 down-strike type-bars, a fixed segment having radial slots receiving the pivotal portions of the type-bars, and upright actuating slides for the type-bars moving vertically in said slots and having a toothed engagement with the type-bars.
  3. In a typewriter, a fixed slotted segment, a down-strike type-bar pivoted in a slot of said segment, and having pinion-teeth, an upright slide movable in such slot and having rack-teeth at its upper end engaging said pinion teeth, and a key-lever connected to the lower part of said slide to lift it for imparting the printing movement to the type-bar. 70
  4. In a typewriter, a slotted segment, 75 down-strike type-bars pivoted in the slots thereof and having pinion teeth in such slots, upright slides having their upper ends in such slots with rack-teeth engaging said pinion teeth and their lower portions projecting below such segment, and key-levers beneath such slides. 80
  5. In a typewriter, a slotted segment, down-strike type-bars pivoted in the slots thereof, upright slides in front of the pivotal portions of said type bars, having their upper ends in such slots and having actuating engagement with the type bars, and an arc-piece fixed in front of said segment to close its slots and hold the slides in operative engagement with the type-bars. 85
  6. In a typewriter, a platen, a series of down-strike type-bars, a fixed segment having radial slots receiving the pivotal portions of the type-bars, and vertically moving actuating slides for the type bars entering said slots, and occupying the front portions of the slots, and a removable part fastened against the front of the segment, and closing the slots to guide the slides and hold 90 the type-bar pivots in place. 95
  7. In a typewriter, a segment having radial slots and a horizontal slot intersecting them, type-bars in said radial slots with their pivots in said horizontal slot, upright 100 slides in said radial slots, having toothed engagement with said type-bars, and an arc-piece fixed to the front of said segment to close said slots, and engaging the fronts of said slides to guide them and hold them 105 in operative engagement with the type-bars, and thereby to hold the pivots in place in said horizontal slot. 110
  8. In a typewriter, a platen, a series of down-strike type-bars, a fixed segment having radial slots receiving the pivotal portions of the type-bars, and an intersecting slot opening away from the platen receiving the pivots of the type-bars, actuating slides for the type-bars moving in said slots, and a band closing the outer ends of said slots and holding the slides in engagement with the type bars and the pivots of the latter in place in said intersecting slot. 115
  9. In a typewriter, a platen, a series of 120 down-strike type-bars, a segment having radial slots receiving the pivotal portions of the type-bars, slides for the type-bars moving in said slots, and a band closing the outer ends of said slots and holding the 125 130

- 8 slides in engagement with the type bars, said band having fingers engaging the respective slides and adjustable individually.
10. In a typewriter, a platen, a series of 8 down-strike type-bars with their pivots, a segment having radial slots receiving the pivotal portions of the type-bars, and a horizontal slot intersecting the radial slots and receiving the pivots of the type bars, 10 upright slides for actuating the type-bars, moving vertically in said slots, and means for holding said slides in engagement with the type bars and thereby retaining said pivots in said horizontal slot.
15. 11. In a typewriter, a type-bar, an upright actuating slide having at its upper part toothed engagement with the type-bar, and a key lever engaging the lower part of said slide, said slide crossing said key lever 20 and having a lateral projection engaging said key lever.
12. In a typewriter, a series of type-bars and actuating slides therefor having toothed engagement therewith, and projecting beneath them, in arc-shaped formation, and key-levers engaging said slides, said slides having lateral ears slotted to receive said key levers, and said ears turned across the planes of the respective levers.
- 25 13. In a typewriter, a type bar and actuating slide therefor, and a key lever engaging said slide, said slide having a lateral ear slotted to receive the key lever, and the key lever entering and confined laterally by 25 the slot in said ear.
14. In a typewriter, a segment having radial slots, type-bars pivoted in said slots, upright slides with their upper ends guided in said slots and having operative engagement with the respective bars and with 40 shoulders on their lower portions, guides for the lower ends of the slides, and key-levers with their rear arms crossing said slides, and entering between such shoulders on the slides, the segment and lower guides 45 being separated to leave a clear space for the movement of the key-levers.
15. In a typewriter, a series of key-levers having on their front arms keys arranged in straight rows, a series of down-strike type-bars moving through approximately a half-circle, a slotted segment having closely-adjacent slots in which said type-bars are pivoted, a series of upright slides having at 50 their upper ends a toothed engagement with said type-bars, and connected at their lower portions to the rear arms of the respective key-levers, the latter arranged in converging order and of varying lengths with intermediate pivots arranged to afford for the 55 respective levers similar ratios of front to rear lever-arms, to give a uniform throw to the types for equal dips of the keys.

In witness whereof, I have hereunto signed my name in the presence of two subscribing witnesses.

RICHARD W. UHLIG.
